US0D1110290S

(12) **United States Design Patent** (10) **Patent No.:** **US D1,110,290 S**
(45) **Date of Patent:** **** Jan. 27, 2026**

(54) **MOTHERBOARD**

(71) Applicant: **Dell Products L.P.**, Round Rock, TX (US)

(72) Inventors: **Jason T. Minehart**, Cedar Park, TX (US); **Dewey Yu**, Pflugerville, TX (US); **Shih-Heng Chen**, Taipei (TW)

(73) Assignee: **Dell Products L.P.**, Round Rock, TX (US)

(**) Term: **15 Years**

(21) Appl. No.: **29/970,546**

(22) Filed: **Oct. 29, 2024**

(51) LOC (15) Cl. **13-03**

(52) U.S. Cl.

USPC **D13/182**

(57) **CLAIM**

The ornamental design for a motherboard, as shown and described.

DESCRIPTION

FIG. 1 is a front perspective view of a motherboard, showing our new design;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof; and,

FIG. 8 is another front perspective view thereof, shown in a used condition with a device shown in broken lines.

Broken lines shown in the drawings illustrate portions of the motherboard, and form no part of the claimed design.

1 Claim, 6 Drawing Sheets
